UNITED STATES PATENT OFFICE

144,601

DESIGN FOR A PAPER PUNCH

John A. Yerkes, New York, N. Y.

Application January 25, 1946, Serial No. 125,984

Term of patent 14 years

(Cl. D74—1)

To all whom it may concern:

Be it known that I, John A. Yerkes, a citizen of the United States, residing in New York city, in the county of New York and State of New York, have invented a new, original, and ornamental Design for a Paper Punch, of which the following is a specification, reference being had to the accompanying drawing, forming part thereof.

I claim:

The ornamental design for a paper punch, as shown.

JOHN A. YERKES.
